UNITED STATES PATENT OFFICE

GEORGE D. MILNE, OF OAK PARK, ILLINOIS, ASSIGNOR TO WESTERN ELECTRIC COMPANY, INCORPORATED, OF NEW YORK, N. Y., A CORPORATION OF NEW YORK

ELECTROMAGNETIC DEVICE

Application filed March 15, 1930. Serial No. 436,182.

This invention relates to an electromagnetic device, and more particularly to an electromagnetic device in which its armature is retained in its attracted positions.

5 An object of this invention is to provide a simple, inexpensive, and efficient electromagnetic device in which its armature is retained in its attracted positions.

In accordance with this object, one embodiment of the invention pertains to an electromagnetic device which comprises a pair of oppositely disposed electromagnets having armatures mechanically interconnected and provided with an off center spring effective 15 for retaining the armatures in their attracted positions.

A clear understanding of the invention will be had from the following description of one specific embodiment thereof when taken 20 in connection with the accompanying drawings, wherein

Fig. 1 is a side view of a pair of oppositely mounted telephone relays, the armatures of which are shown connected to a mechanical retaining apparatus;

Fig. 2 is a sectional view of the connected relays, taken on the line 2—2 of Fig. 1 to show said retaining apparatus in plan, and

Fig. 3 is an end view of the apparatus.

30 Referring now to the drawings wherein like reference numerals designate similar parts throughout the several figures, there is disclosed a pair of telephone relays having coils 5 and 6, respectively, and inwardly releasing or opening U-shaped armatures 7 and 8, the relays being secured by screws 9 and 10 to a mounting plate 11. These relays are provided with contact springs 12 and 13, respectively, which have contact points at their free 35 ends and which have terminal connectors 17 and 19 extending to the left through apertures 14 in the mounting plate. The coils 5 and 6 terminate in connectors 15 and 16 (Fig. 1). The right hand ends of the armatures 7 and 8 are offset as especially shown in Fig. 3 to conform to the shape of and cooperate with pole pieces or core extensions 20 and 21, and plungers 22 and 23 extend from the armatures 7 and 8, respectively, through apertures 50 in the contact springs 12 and 13 to actuate

these springs to control the circuits which may be connected to the terminal connectors at the left hand ends thereof. Bolt studs 24 and 25 are secured to the pole pieces 20 and 21 to limit the inward or releasing movement of the armatures.

55 The contemplated apparatus for mechanically retaining the relays in their attracted positions includes a U-shaped support 26 which is secured to studs 18 which are mounted on the mounting plate 11 by screws 27, a cross piece 28 being secured to the sides of the support for bracing purposes. A crank shaft 29 is journaled in the outer end of the support 26 and has two eccentric or crank portions to which are connected links 30 and 31 which are coupled to yokes 32 and 33, respectively, which extend over the sides of the pole pieces 20 and 21 for guiding purposes, which yokes are secured to the ends of the armatures 7 and 8. A crank arm or lever 34 extends integrally from one end of the crank shaft 29 and is limited in its upward and downward movement or throw by a V-shaped member 35 secured to the support 26. A coil spring 36 is secured to the crank arm 34 and at its other end to an adjusting bolt 37 threaded to the mounting plate 11.

60 In the operation of the above described apparatus the circuits to be controlled by the electromagnetic device are connected to the terminal connectors 17 of the contact springs 12, and when the upper relay is to be actuated for controlling these circuits current is momentarily applied from a suitable power supply circuit to the terminals 15 of the coil 5, which current momentarily attracts the armature 7 and moves the crank arm 34 to its upper position as shown in the drawings. The coil spring 36 then retains the armature 7 in this 65 attracted position through connection with the link 30 and the yoke 32, it being noted that no further energizing current is required in the coil 5, since the spring 36 maintains the armature in this position. When the armature 7 is to be released current is applied to the terminals 16 of the coil 6 of the lower relay through a suitable power circuit which may be connected therewith to attract the armature 8 and thus actuate the crank shaft 70

29 and move the crank arm 34 to its lower position, the spring 36 then retaining the crank arm 34 in this position. Thus, it is apparent that the crank shaft, spring, and link structure provided by this invention 5 mechanically retains the relay armature in its attracted position to eliminate the necessity of continuous energizing current being applied thereto. The contact springs 13 of 10 the lower relay 6 may also be connected to circuits to be controlled similarly to the contact springs 12, the operation with respect thereto being the same as that above described.

15 From the foregoing description the construction and operation of the apparatus is believed to be apparent, but it will of course be understood that the invention is to be limited only by the scope of the appended 20 claims.

What is claimed is:

1. In an electromagnetic device, a coil, an armature attracted thereby, means mounted adjacent the armature and pivoted about its 25 own axis, means connecting the pivotal means to the armature, and a resilient member secured to the pivotal means for retaining the armature in attracted position.
2. In an electromagnetic device, a coil, an 30 armature attracted thereby, an eccentric member mounted adjacent the armature, means connecting the eccentric member to the armature, and a coiled resilient member secured to the eccentric member for retaining 35 the armature in attracted position.
3. In an electromagnetic device, a coil, an armature attracted thereby, a crank shaft mounted adjacent the armature, means linking the crank shaft with the armature, and a 40 resilient member connected to the crank shaft for retaining the armature in attracted position.
4. In an electromagnetic device, a coil, an armature attracted thereby, a support mounted 45 adjacent the armature, a crank shaft journaled in the support, means linking the crank shaft with the armature, and a resilient member connected to the crank shaft for yieldingly retaining the armature in attracted 50 position.
5. In an electromagnetic device, a pair of adjacently positioned coils, armatures supported adjoining the coils and movable independently by the action of said coils to 55 two positions, pivotal means mounted between the armatures and linked therewith, and a resilient member directly connected with the pivotal means for retaining the armatures in either position to which they 60 are attracted by the coils.
6. In a relay, a pair of adjacently mounted coils, an armature supported adjoining each coil, a support mounted between the coils, a crank shaft having an extending crank arm 65 and journaled in the support, means linking

each armature with the crank shaft, and a coiled spring connected to the extending arm of the crank shaft for retaining armatures in either position to which they are moved by the coils.

7. In an electric relay, an armature movable to either of two positions, electromagnetic means for moving the armature from one to the other of said positions, a member rotatably mounted adjacent the armature and connected thereto, and yielding means cooperating with the rotatable member to maintain the armature in either of said positions to which it may be moved.

8. In an electromagnetic device, a coil, an armature actuated upon the energization of said coil, a pivotally mounted eccentric member positioned adjacent the armature, and a resilient means operative through the eccentric member for retaining the armature in its attracted position.

In witness whereof, I hereunto subscribe my name this 27th day of February, A. D. 1930.

GEORGE D. MILNE.
